Assistant Examiner — Aula Soroush

(57) **CLAIM**

The ornamental design for a pet crate, as shown and described.

DESCRIPTION

FIG. 1 is a front, right, and top perspective view of a pet crate, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an encircled area labeled "9" in FIG. 1;

FIG. 10 is an enlarged view of an encircled area labeled "10" in FIG. 2;

FIG. 11 is a front, right and top perspective view of a second embodiment of a pet crate, showing my new design;

FIG. 12 is a rear, left, and bottom perspective view thereof;

FIG. 13 is a front view thereof;

FIG. 14 is a rear view thereof;

FIG. 15 is a left side elevation view thereof;

FIG. 16 is a right side elevation view thereof;

FIG. 17 is a top plan view thereof;

FIG. 18 is a bottom plan view thereof;

FIG. 19 is an enlarged view of an encircled area labeled "19" in FIG. 11; and,

FIG. 20 is an enlarged view of an encircled area labeled "20" in FIG. 12.

The broken lines depict portions of the pet crate in which the design is embodied that form no part of the claimed design.

1 Claim, 20 Drawing Sheets
